HAMILTON E. TOWLE, OF NEW YORK, N. Y.

Letters Patent No. 102,882, dated May 10, 1870.

IMPROVEMENT IN LEVELING AND GRADING INSTRUMENT.

The Schedule referred to in these Letters Patent and making part of the same.

I, HAMILTON E. TOWLE, of New York, in the county and State of New York, have invented certain Improvements in Surveying Instruments, of which the following is a specification.

Nature and Objects of the Invention.

The object of the said invention is to simplify the construction of a leveling instrument, by which it may be furnished at a comparatively cheap rate, and be used with facility and exactitude by persons who may be destitute of professional experience, or unfitted by the want of technical education for operating with such instruments as ordinarily constructed.

In addition to the minor details of construction and adjustment, the first of the said improvements consists in a peculiar ball-and-socket joint in which a divided ball possesses all the advantages of the ordinary joint with an entire ball, and is entirely free from the jerky motion that is almost inseparable from the latter.

With the ordinary joint the first motion requires a greater power to effect than a continuation of the movement, and the excess of power, when only a slight movement is required, is likely to move the instrument too far. Even when the joint may have been carefully ground, the gumming of the lubricating material, or the presence of dust or grit, will soon destroy the effects of good workmanship.

The variations in the resistance require variations in the force, which are difficult to determine, and render the adjustment a matter of experiment instead of a matter of precision. By dividing the ball, however, and placing a spring between the parts, the tension of the spring remains practically unaltered, and the resistance to the movement in the socket is similarly uniform within the limit adjusted by the clamp-screw of the socket.

By dividing the ball at right angles to the axis that passes through the neck, and placing between the parts an axial spindle common to both parts, an effort to move the instrument around that axis is resisted only by the friction on the small portion of the part of the ball annexed to the neck, that is, within the socket, and, as this is much less than the friction on the entire surface within the socket, say about one-fifth, for example, the instrument may be turned around the entire circle with one-fifth of the power that would be required to complete a revolution in any other plane in which both parts of the ball must necessarily be moved, and the difference between these two extremes of the exercise of power is sufficient to insure accuracy in the hands of even the most careless.

This improvement in the construction of ball-and-socket joints is applicable to all instruments and machines in which such joints may be used.

Another of the said improvements consists in the construction of the sights, by which they are mounted on screw-shanks, the threads of which have a definite relation to the distance between the sights.

Sights for any purpose usually consist of slides adjusted within frames by screws, and marked with the required graduations on the slides or frames, and, although these graduations necessarily have a definite relation to the distance between the sights, there is nothing in the construction of the parts to indicate this relation, or the effect of any change in the arrangement or adjustment of the parts.

The improvement in sights, not only for surveying instruments but for all applications of sights, consists in establishing the relation in the construction of the instrument, and independent of subsequent adjustment, by means of revolving sights mounted on screw-shanks in which the relation between the adjustment of the sight and the distance is determined by the thread, and is altered the same in amount, either more or less, at each rotation of either of the sights, and may be doubled by the rotation of both of them. For example, if the sights are ten inches apart, and the threads are one-tenth of an inch in pitch, each revolution of one sight alters the grade or level one foot in a hundred, and the reverse revolution of the other sight continues the increment an equal amount to give the instrument a doubled range. A half-revolution of course alters the grade but six inches in the hundred feet. The stems or shanks of the sights are flattened, so that, when held by a set-screw, the square end of the screw sets the sight square, and the flattened sides furnish a convenient place for the marking of the graduations.

In levels, as ordinarily constructed, the adjusting-screw, in setting the level, lifts the end of the instrument, and it must be free to rise. If, therefore, by any accident the instrument be turned upside down, the parts will swing apart, and may be strained, and perhaps injured. With the light instrument attainable with these improvements, the weight of the bar in which the tube is secured may be carried on a spring, and the adjustment may be effected by means of a screw that restrains the spring and holds the parts together in any position, operating, in fact, in combination with the spring, in just the reverse manner to the ordinary adjusting-screw that has no spring.

Another improvement consists in constructing a level with a wood-screw, by which it may be mounted on a stake, or otherwise, without a tripod. It is sometimes convenient to use the instrument in places where there may not be room enough for a tripod, as, for instance, close to a rock or wall. Wood screws have been hitherto essayed for the purpose simply of securing telescopic and other instruments in position,

but it is obvious that they cannot be used independent of other adjustment in an instrument to sweep around a horizontal plane. In combination with the divided ball above described, the wood-screw may be used as effectively as any tripod with its comparatively complicated set-screw adjustment, and, with its application to a leveling instrument, a stake that may be driven close to an obstruction, where there would otherwise be insufficient room, is the only support required.

Description of the Drawings.

Figure 1 represents a level made according to my said improvement;

Figure 2 is an enlarged view of the eye-sight;

Figure 3 is an enlarged view of the object-sight;

Figure 4 is a cross-section of the stem or shank of the sights at x x , fig. 2.

Figures 5 and 6 show a modification of the ball in vertical and horizontal section; and

Figures 7 and 8 show another modification of the same.

The bar B, in which the bubble-tube is secured, carries the sights at each end constructed with flattened screw-stems, G, in the manner described, and secured in any position by the set-screws i. I prefer to cement the tube in a supplementary cup set with one or more

screws inside a cavity in the bar, with the whole covered by the ordinary plate.

The bar, with the sights O and I, and the tube L, is carried on the joint J, and is sustained by the spring S, and held by the screw s adjusted by the thumb-screw nut T.

The wood-screw P carries the ball-and-socket joint, the socket part being made with a clamp and screw, in the usual way. The ball is divided, and has a spring between the parts, and a small pin as an axis, common to both of them. The socket may be lined, if desired, with leather or other material.

Claims.

I claim as my invention—

1. A ball-and-socket joint, with a divided ball, with or without an interposed spring, substantially as described, and either with or without an axial spindle.

2. The combination and arrangement of the graduated adjustable sights, having screw-shanks, the threads of which have a determined relation to their position, with a leveling instrument for operation substantially as described.

HAMILTON E. TOWLE.
